UNITED STATES PATENT OFFICE

109,605

DESIGN FOR A SMOKING DEVICE

Giuseppe Cippico, Rome, Italy, assignor to Zeus Corporation, New York, N. Y., a corporation of Delaware

Application February 7, 1938, Serial No. 74,928

Term of patent 14 years

To all whom it may concern:

Be it known that I, Giuseppe Cippico, a citizen of Italy, residing at Rome, in the Province of Rome and Kingdom of Italy, have invented a new, original, and ornamental Design for a Smoking Device, of which the following is a specification, reference being had to the accompanying drawing, forming a part thereof, in which:

Fig. 1 represents a side elevational view, Fig. 2 represents a plan view, and Fig. 3 represents an end elevational view, as viewed from the right of Fig. 2, of the smoking device embodying my new design.

I claim:

The ornamental design for a smoking device substantially as shown.

GIUSEPPE CIPPICO.

CERTIFICATE OF CORRECTION.
